CLAIM

The ornamental design for a golf club head, as shown and described.

DESCRIPTION

FIG. 1 is a rear elevation view of a golf club head;
FIG. 2 is a front elevation view thereof;
FIG. 3 is a top plan view thereof;
FIG. 4 is a bottom plan view thereof;
FIG. 5 is a toe-side elevation view thereof;
FIG. 6 is a heel-side elevation view thereof;
FIG. 7 is a top perspective view thereof; and,
FIG. 8 is a top perspective view showing the golf club head in use.
The broken lines shown depict portions of the golf club head and environment and form no part of the claimed design.

1 Claim, 6 Drawing Sheets
